(57) **CLAIM**

The ornamental design for a slanted base of endoscope tip attachment, as shown and described.

DESCRIPTION

FIG. 1 is a top, front, right perspective view of a slanted base of endoscope tip attachment, showing our new design, where the slanted base of endoscope tip attachment is shown with an unclaimed endoscope inserted;

FIG. 2 is a bottom, rear, left perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines of even length shown in the drawings depict portions of the slanted base of endoscope tip attachment that form no part of the claimed design. The uneven length broken lines depict the boundary of the claimed design and form no part thereof.
